UNITED STATES PATENT OFFICE.

CLIFFORD F. RANDOLPH AND NICHOLAS MARCALUS, OF PLAINFIELD, NEW JERSEY,
ASSIGNORS TO NILES-BEMENT-POND COMPANY, OF NEW YORK, N. Y., A CORPORATION
OF NEW JERSEY.

TOOL HOLDER.

Application filed October 24, 1923. Serial No. 670,535.

This invention relates to tool holders for planers and like machines. In these machines, the tool is ordinarily clamped to the tool holder block by means of one or more 5 clamping plates secured by a plurality of clamping bolts. These clamping bolts must be loosened to change the tool and such operation requires considerable time and energy. One object of our invention is to provide an 10 improved tool clamping means including a single operating element for readily clamping or releasing the tool relative to its holder.

More specifically, it is an object of the invention to provide a tool clamping means 15 comprising one or more rotary eccentric elements and a single operating hand wheel for rotating the elements to clamp and unclamp the tool relative to its holder.

Another object of the invention is to provide improved means for rotatably adjusting a tool holder block about its pivot or 20 swivel center and means for clamping the block in adjusted position, both such means preferably being operated from a single hand 25 wheel.

With the above and other objects in view, our invention consists in the features of construction and operation set forth in the following specification and illustrated in the 30 accompanying drawing. In such drawing annexed hereto and forming a part of this specification, we have shown one embodiment of our invention but it will be understood that the invention can be otherwise embodied 35 and that the drawing is not to be construed as defining or limiting the scope of the invention, the claims appended to this specification being relied upon for that purpose.

Referring to the figures of the drawing: 40 Figure 1 is a side elevation of a tool holder comprising the invention.

Fig. 2 is a front elevation thereof.

Fig. 3 is a vertical sectional view thereof on line 3—3 of Fig. 2.

Fig. 4 is a fragmentary view of Fig. 3 but showing the mechanism illustrated in another position.

Fig. 5 is a cross section of the tool holder taken on line 5—5 of Fig. 3.

Fig. 6 is an enlarged fragmentary sectional view taken on line 6—6 of Fig. 2.

Referring more specifically to the drawing, 1 indicates a tool support or slide adapted to be mounted for vertical movement in a 55 saddle 2, the slide being provided with a

bearing 3 for receiving the usual supporting and adjusting screw 4. This screw is adapted to be journaled in the bearing 3 and threadedly engage a nut 5 on the saddle. Mounted on a bolt 6 in the slide so that it 60 may be swivelled thereon is a block 7. A tool holder 8 is pivoted to this block at 9. The improvements comprising our invention are improved means for clamping the tool or tools in place in the holder 8 and improved means for adjusting the block 7 on its pivot 6 and for securing the block in its adjusted position. The details of these mechanisms as illustrated in the drawing 65 will now be described.

Rotatably supported in the slide 1 and projecting forwardly therefrom is a screw threaded shaft 10. A pinion 11 threadedly mounted on this shaft is in mesh with rack teeth 12 on the block 7. A shaft 13 is rotatably mounted in a forwardly extending portion 14 of the slide. An eccentric portion of this shaft engages against a plate 15 on the block 7 for clamping the block to the slide. A yoke 16 projects laterally from the 70 shaft 13 and engages an annular groove 17 in the pinion. Keyed to the shaft 10 within the portion 14 of the slide is the hub of a hand wheel or capstan 18. A spring pressed 75 detent 19 is adapted to hold the wheel 18 in either of two positions axially. The inner end of the hub is provided with a tooth 20 for engaging with a cooperating tooth 21 on the pinion as hereinafter described.

The operation of the mechanism just described is as follows: As illustrated in Fig. 3, the block 7 is clamped to the slide 1. When it is desired to adjust the block about its pivot 6, the shaft 10 is rotated anti-clockwise. This operation draws the pinion 11 80 outwardly which rotates the clamping shaft 13 and releases the block 7. When the pinion has been brought to the position shown in Fig. 4, the hub 18 is moved inwardly to engage its tooth 20 with the tooth 21 of the 85 pinion. Rotation of the capstan will now 90 rotate the pinion and screw as a unit and adjust the block about its axis 6. It will be noted that the pinion is never out of mesh with the rack teeth 12. When the block 95 has been adjusted to the desired position, the hub 18 is withdrawn to the position shown in Fig. 3. Rotation of the capstan will now rotate only the screw. Rotation 100 of the capstan and screw clockwise will 105 operate the slide 1. Rotation of the capstan and screw counter-clockwise will 110

erate to move the pinion inwardly and rotate the clamping shaft 13 in a direction to clamp the block in its adjusted position, as shown in Fig. 3.

5 In the drawing, we have shown two tools 22 and 23 as supported in the tool holder 5, the tool 23 being positioned to cut deeper than the tool 22. In certain planing operations where a heavy cut is to be taken, it is 10 of considerable advantage to take such cut with two tools rather than to cut the full depth with a single tool. In such operation, the first tool 22 is adjusted to take a portion of the cut and the tool 23 completes the cut. 15 By this method, the cutting operation is performed with greater smoothness and with considerably less power and vibration than when using a single tool. It will be understood, however, that the tool holder illustrated is adapted to support one or a plurality of tools as may be desired.

The tool holder 8 is recessed at 24 for receiving the tools 22 and 23. A serrated plate 25 is preferably provided for backing 25 up the tool 23. A spacer block 26 with a serrated plate 27 therein is provided between the two tools. Two blocks 28 are supported by bolts 29 forwardly of the tool 22, the forward face of each block being recessed to 30 receive the eccentric portion of a clamping shaft 30 therein. A spring 31 surrounding each bolt 29 serves to hold each block 28 in contact with its eccentric.

One end of each shaft 30 has an arm 32 35 projecting laterally therefrom and respectively engaging nuts 33. One nut 33 is threaded to the right hand threads 34 of a shaft 35 and the other nut 33 is threaded to the left hand threads 36 of the shaft. The 40 shaft is mounted for free axial movement in the tool holder and can be rotated by means of a handle element 37.

In Fig. 3 the tools and mechanism just described are shown in the unclamped position. 45 To clamp the tools in the holder, it is only necessary to rotate the hand wheel 37 anti-clockwise. Such rotation draws the nuts 33 together and swings the arms 32 toward each other. The eccentric shafts are thereby rotated in a manner to firmly force the blocks 50 28 toward the tools. Since the shaft 35 is freely movable axially, the clamping effect of each shaft 30 operates directly against the other shaft whereby the two shafts are 55 operated with equal or balanced forces. The rear face of the serrated plate 27 is curved transversely whereby the same automatically adjusts itself to firmly grip both tools flatly between their holding plates. To release 60 the tools, it is only necessary to rotate the hand wheel 37 in a clockwise direction.

It will be understood that the tool holder or clapper box 8 is adapted to move outwardly about its pivot 9 to prevent marring 65 of the work on the idle or non-cutting stroke

of the work or tools. As illustrated in Fig. 3, a projection 38 is preferably formed on the block 7 and recessed in a manner to receive a projecting portion 39 of the tool holder 8. The projection 39 is adapted to 70 swing within the projection 38 and these two projections are provided with engaging surfaces at 40. The surfaces 40 therefore provide a metal to metal contact which backs up the tool holder in a manner to relieve the 75 pivot 9 from the load of upward thrust of the tools.

What we claim is:

1. A tool holder comprising in combination, a block adapted to receive a cutting tool therein, a plurality of rotary eccentrics operative against the tool to clamp the same in the block, and a unitary hand operated means for rotating the eccentrics. 80

2. A tool holder comprising in combination, a block adapted to receive a cutting tool therein, a plurality of rotary eccentrics operative against the tool to clamp the same in the block, and a unitary screw threaded means for rotating the eccentrics. 85

3. A tool holder comprising in combination, a block adapted to receive a cutting tool therein, a pair of rotary eccentrics operative against the tool to clamp the same in the block, a shaft provided with right 95 and left hand screw threads thereon, and a pair of nuts respectively connected to the said eccentrics and engaging the said screw threads.

4. A tool holder comprising in combination, a block adapted to receive a cutting tool therein, a pair of rotary eccentrics operative against the tool to clamp the same in the block, each eccentric being provided with a laterally extending arm, a shaft provided with right and left hand screw threads thereon, and a pair of nuts respectively engaging the said screw threads and connected to the free ends of the said arms, the shaft being mounted for free sliding movement 105 axially whereby the eccentrics will be operated with balanced forces. 110

5. A tool holder comprising in combination, a block adapted to receive a cutting tool therein, a plurality of rotary elements 115 operative against the tool to clamp the same in the block, and a unitary hand operated means for rotating the elements.

6. A tool holder comprising in combination, a support, a tool holding block pivotally mounted thereon, means for adjusting the block about its pivot as a center, means for clamping the block in adjusted position, and a unitary hand operated means for operating the two first mentioned means. 120

7. A tool holder comprising in combination, a support, a tool holding block pivotally mounted thereon, a pinion for adjusting the block about its pivot as a center, pivoted means for clamping the block in 130

adjusted position, and a unitary hand operated means for rotating the pinion to adjust the block and for moving the clamping means about its pivot to clamp the block.

8. A tool holder comprising in combination, a support, a tool holding block pivotally mounted thereon, a shaft mounted in the support, a pinion on the shaft engaging 10 teeth in the block for adjusting the block about its pivot as a center, means for clamping the block in adjusted position, and an operating element on the shaft for operating both the pinion and clamping means.
- 15 9. A tool holder comprising in combination, a support, a tool holding block pivotally mounted thereon, a shaft mounted in the support, a pinion screw threadedly mounted on the shaft and engaging teeth 20 in the block for adjusting the block about

its pivot as a center, means connected to the pinion for clamping the block in adjusted position, and an operating element on the shaft for rotating the shaft and pinion.

25

10. A tool holder comprising in combination, a support, a tool holding block pivotally mounted thereon, a shaft mounted in the support, a pinion screw threadedly mounted on the shaft and engaging teeth 30 in the block for adjusting the block about its pivot as a center, means connected to the pinion for clamping the block in adjusted position, and means for rotating the shaft in the pinion or for rotating the pinion and shaft as a unit.

In testimony whereof, we hereto affix our signatures.

CLIFFORD F. RANDOLPH.
NICHOLAS MARCALUS.
